WASHING MACHINE

James B. Kirby, West Richfield, Ohio, assignor,
by mesne assignments, to The Apex Electrical
Manufacturing Company, Cleveland, Ohio, a
corporation of Ohio, as trustee

Application October 29, 1932, Serial No. 640,253

11 Claims. (Cl. 68—15)

This invention relates to clothes washing machines and in particular machines of the type wherein there is provided both washing and wringing mechanisms.

5 One of the objects of this invention is to provide in a machine of the type defined, a generally simplified and inexpensive operating mechanism.

Another object of this invention is to provide in a machine of the class defined, an efficient and 10 quietly operating mechanism.

Another object of this invention is to provide in a machine of the type defined, an improved form 15 of operation mechanism.

Another object of this invention is to provide 20 in a machine of the type defined, an improved form of driving mechanism for the washing and wringing devices of the machine.

Another object of my invention is to provide 25 in a washing machine gearing, an improved form of variable stroke agitator driving mechanism.

Another object of my invention is to provide in a machine of the type defined, an improved form 30 of agitator construction.

Another object of my invention is to provide in 35 a machine of the type defined, improved liquid handling means.

Another object of my invention is to provide in a machine of the type defined, an improved form 40 of wringer driving mechanism.

Stated in general terms the machine chosen to 45 illustrate one mode of practicing my invention comprises a gyrator type washing machine with mechanism for operating an oscillatable gyrator located beneath the tub of the machine, such mechanism also serving to operate a wringer located above the tub of the machine. This mechanism comprises a motor arranged on a vertical axis and having a pulley for driving a belt by means of which a pump, a wringer drive reduction gear, and an idler pulley are driven. The idler pulley carries a relatively small pulley from which a second belt transmits the power of the motor to a larger pulley. The larger pulley is provided with a crank pin which is connected by 50 means of variable stroke mechanism to the agitator shaft of the machine whereby the stroke of the agitator may be adjusted selectively from zero to maximum oscillation.

A further object of my invention is to provide 55 in a machine of the type defined, an improved arrangement for supporting and mounting the operating mechanism of the machine whereby such mechanism can be assembled and tested independently of the machine; the same forming with its base an independent and operative unit

which is applied to the machine by simply securing such base to the frame of the machine.

With these and other objects in view, the invention consists in the novel construction, arrangement and combination of parts, hereinafter illustrated and described and some of its embodiments in the accompanying drawings, and particularly pointed out in the appended claims.

5 Referring to the drawings, Figure 1 is a side elevational view partly in section, showing a combined washing and wringing machine illustrating one mode of practicing my invention.

Figure 2 is a plan view of the agitator used in the machine shown in Figure 1.

Figure 3 is an enlarged sectional view of the 15 wringer driving reduction gear taken on line 3—3 of Figure 1.

Figure 4 is a plan view partly in section, of the underside of the machine corresponding to line 20 4—4 of Figure 1 and showing the driving mechanism of the machine in full "on" position.

Figure 5 is an enlarged sectional view of the 25 variable stroke mechanism taken on line 5—5 of Figure 4.

Figure 6 is a plan view of a slightly modified 30 form of variable stroke mechanism corresponding generally to the mechanism shown in Figure 4 and showing the parts in the full "off" position.

Figure 7 is an enlarged sectional view taken on line 7—7 of Figure 4 illustrating certain details 35 of the variable stroke mechanism; and

Figure 8 is an enlarged sectional view taken on line 8—8 of Figure 4 illustrating certain details of the belt tension adjusting mechanism.

The washing machine illustrated in Figure 1 40 comprises a washing tub or casing 1 carried upon a suitable frame 2, supported by legs 3, having casters 4 at their lower ends. The machine is provided with a wringer 5 of suitable design mounted so as to swing above the tub 1 about the axis of its supporting column 6 under control of a locking lever 7. A control lever 8 is provided for controlling the stopping and forward or reverse driving connections of the wringer.

The tub is provided with a cover 9 and within 45 the tub there is provided an agitator 10 mounted for reversely rotary movement about a vertical axis. This agitator has a plurality of radially extending upstanding vanes 11 projecting from an apertured base portion 12. The base being 50 formed with openings so as to allow free circulation of water therethrough. The corrugations formed by spaced strips 13 of the base cooperate to exert a scrubbing action on the clothes as they were forced against the surface of this 55

member by reason of downward and outward circulation induced in the water of the tub by the vanes 11 and also by reason of the centrifugal action of the strips 13 and 13a.

5 A shaft 14 extends through and is journaled in a bearing 15 carried in a leak-proof relation about aligned central apertures formed in the bottom of the tub and in the base 2. The agitator 10 rests on the top of the bearing 15. The bearing member is held in leak-proof position in the tub by means of a lock nut 16 and the co-operating flange 62 of the bearing member. A washer 16a is provided as a spacing member between the tub 1 and the base 2. Suitable sealing gaskets (not shown) may be used between the tub and the elements 16 and 16a. The agitator shaft 14 is operatively connected to movement converting mechanism which will be described in detail presently.

20 The washer mechanism is driven by means of an electric motor 17 or other suitable source of motive power by way of the power transmission belts 18 and 19. The belt 18 is driven by the motor pulley 20 and it in turn serves to drive the pulley 21 of a fluid pump 22 suspended from a control valve 23. The belt 18 also engages in driving relation the pulley 24 of a crank shaft 25 having a crank 26 at its upper end. A gyro-tative externally toothed gear 27 is mounted for rotation on the crank 26 and also for revolution about the axis of the shaft 26. The teeth of the gear 27 engage with the teeth of a fixed internal gear 28 and as the gear 27 is rapidly rolled about in the gear 28 it is slowly rotated about the axis of the crank 26.

40 The gyro-tative gear 27 is connected in driving relation to a vertical shaft 29 by means of the universal joint 30. The upper end of the shaft 29 is connected in driving relation with the vertical wringer driving shaft 31 by means of a second universal joint 31a. Thus upon rotation of the crank 26 the gear 27 rolls around the internal gear and provides a compact, inexpensive and efficient speed reducing device for driving the vertical shaft 29.

45 The inlet side of the pump 22 is connected to the bottom of the tub by means of the valve 23, which has a control handle 32. The outlet side of the pump is connected to a drain hose 33 having a gooseneck 34 swiveled to its other end and received in a pocket 35 formed to provide an aperture through the side wall of the tub.

The belt 18 serves to drive a speed reducing idler pulley 36 upon which is formed a small 55 pulley 37, which engages with the belt 19 and thus serves to rotate a large speed reducing pulley 38 by means of this belt. The pulley 38 is rotatably journaled on a stub shaft 39 in line with the axis of the tub 1. The central portion 60 of the pulley 38 has an upstanding eccentric pin 40 to which is journaled a pitman 41. The pitman 41 is pivotally connected at 42 to an oscillatable guideway 43 in which is received a slide block 44.

65 The slide block 44 is pivotally connected at 45 to an adjusting lever 46 and also to a second pitman 47 which is at its other end pivotally connected at 48 to a crank 49 fixedly secured to the lower end of the agitator shaft so that the 70 reciprocating movement of the pitman 47 is transmitted to the crank 49. A control lever 50 is journaled for movement about the axis of the tub 1 and it has an operating handle 51 and a pivotal connection 52 with the lever 46 whereby 75 means are provided for moving the slide block

44 and its pivot 45 along the channeled guideway 43a of the lever 43 so that the length of stroke of the pitman 47 can be adjusted from zero to maximum, it being at zero for the position shown in Figure 6 when the pivot point 45 corresponds to the pivotal point 53 of the lever 43 and at maximum when the parts occupy the position shown in Figure 4. The base of the machine is provided with suitable notches 54 so that the control member 51 and the associated parts can be maintained in various adjusted positions.

5 In Figure 4 the variable stroke mechanism is shown in its "on" or full stroke position. In Figure 6 the mechanism is shown in its "off" position and no movement whatever is transmitted to the agitator or its shaft. The form of construction shown in Figure 6 differs in that the crank 49 is replaced by a pinion 55 and the pitman 47a is provided with rack teeth 56 in operative engagement with the teeth of the pinion 55. This form of gearing is provided to increase the stroke of the agitator 10 to approximately one half of a turn. The rack bar 47a is held in operative relation with respect of the pinion 55 by means of a stirrup 57 having a bearing portion 58 journaled about the agitator shaft 15 extended, at points above and below the pinion 55. The other parts of the operating mechanism for the agitator shaft are exactly the same as the parts shown in Figure 4.

30 The agitator shaft 15 is provided with suitable packing 59 carried in the enlarged lower portion of the bearing member 15. This packing is held in position by means of a packing gland 60, a spring 60a and an apertured nut 61. The tub 1 and base 2 are provided with aligned central apertures for the reception of the bearing member 15. A plate 2a is welded about the base aperture to reinforce it at this point. The bearing member 15 is securely held in position by means of the nut 16 which serves to rigidly clamp the bearing member to the base and tub of the machine. The bearing member 15 is provided with an external bearing surface 63 upon which is journaled the operating lever 50.

40 The idler pulley 36 is mounted for rotation on a shaft 64 fixedly secured to a plate 65 eccentrically of a pin 66 upon which the plate is journaled. A second plate 67 is carried by the pin 66 and it cooperates with the plate 65 to hold the pin 66 and the stud shaft 64 in alignment. The pin 66 is slidably received in a slot 68 formed in a supporting member 69. On the underside of the supporting plate 69 there is provided a threaded and swiveled member 70 for the reception of the screw threaded rod 71. This rod engages at one end of the member 66 and at its other end is provided with a knurled adjustment handle 72, so that by turning the adjustment handle 72 the tension on the belts 18 and 19 can be adjusted. The plate 65 is movable about the pin 66 and in this manner the pulleys 36 and 37 can accommodate themselves to equalize the tension of the belts 18 and 19.

45 Practically all of the operating elements of the machine are mounted on the plate 69 thus permitting the assembling and testing of the mechanism as a unit apart from the rest of the machine. The assembled operating unit is applied to the rest of the machine by holding the plate 69 in position to receive the bolts 73. After these bolts 73 are tightened the nut 16 is applied to the bearing 15 and the belt 18 is slipped over the pulleys 21 and 24 whereupon the machine is in condition for operation.

50 Furthermore it is to be understood that the

particular forms of apparatus shown and described, and the particular procedure set forth are presented for purposes of explanation and that various modifications of said apparatus and procedure can be made without departure from my invention as described in the appended claims.

Having thus described my invention what I claim is:

1. In a machine of the class described, a framework structure including a base member and floor engaging supports connected thereto and projecting downwardly therefrom, a plate secured beneath said base member in a readily detachable manner, and an operating mechanism comprising independently mounted parts, some secured to said base member and others secured to said plate, such independently mounted parts of said mechanism being non-fixedly joined to each other in operative relation whereby certain of the parts of said mechanism may be readily removed from the machine upon the detachment of said plate from said base member.

2. In a machine of the class described, a tub, a supporting structure therefor including a flanged base member, a plate secured beneath said base member in a readily detachable manner, and an operating mechanism comprising independently mounted parts, some secured to said base member and others secured to said plate, such independently mounted parts of said mechanism being non-fixedly connected to each other in operative relation by slidably interfitting mechanical connections and power transmission belt means, whereby certain of the parts of said mechanism may be readily removed from the machine upon the detachment of said plate from said base member, the flanged portion of said base member extending about said mechanism in sealing relation.

3. In a machine of the class described, a framework structure including a base member and a plurality of supporting legs attached thereto and projecting downwardly therefrom, a plate secured beneath said base member in a readily detachable manner, and an operating mechanism comprising independently mounted parts, some secured to said base member and others including a motor secured to said plate, such independently mounted parts of said mechanism being non-fixedly connected to each other in operative relation by means of oscillatable driving and driven elements of the mechanism whereby certain of the parts of said mechanism may be readily removed from the machine upon the detachment of said plate from said base member.

4. In a machine of the class described, a base, a plate secured to said base in a readily detachable manner, and an operating mechanism comprising independently mounted parts, some secured to said base and others secured to said plate, such parts of said mechanism being joined to each other in operative relation by slidably interfitting mechanical connections and power transmission belt means, and means for adjusting such mechanical connections for controlling the operation of the machine.

5. In a machine of the class described, a base, a plate secured to said base in a readily detachable manner, and an operating mechanism comprising independently mounted parts, some secured to said base and others secured to said plate, such parts of said mechanism being joined to each other in operative relation by slidably

interfitting mechanical connections and power transmission belt means, and means turnable about the center of said base for adjusting such mechanical connections for controlling the operation of the machine.

6. In a machine of the class described, a base, a plate secured to said base in a readily detachable manner, and an operating mechanism comprising independently mounted parts, some secured to said base and others secured to said plate, such parts of said mechanism being joined to each other in operative relation by slidably interfitting mechanical connections and power transmission belt means, and means including an operating handle accessible exteriorly of the machine for adjusting such mechanical connections for controlling the operation of the machine.

7. In a washing machine of the type having a tub for clothes and washing fluid and an agitator oscillatably positioned therein, driving mechanism for the agitator comprising a motor having a belt pulley on its shaft, a belt connecting the pulley of said motor to the larger of a pair of joined and axially aligned pulleys rotatably carried by the machine, a fourth pulley of considerably larger size than the largest of the previously mentioned pulleys positioned centrally below the tub, a belt connecting said fourth pulley to the smaller of said aligned pulleys, motion-converting driving mechanism for said agitator including a member pivoted to said fourth pulley between the periphery and axis thereof, and means for shifting the axis of said aligned pulleys for simultaneously adjusting the tension of said belts.

8. In a washing machine of the type having a tub for clothes and washing fluid and an agitator oscillatably positioned therein, driving mechanism for the agitator comprising a motor having a belt pulley on its shaft, a belt connecting the pulley of said motor to the larger of a pair of joined and axially aligned pulleys rotatably carried by the machine, a fourth pulley of considerably larger size than the previously mentioned pulleys positioned centrally below the tub, a belt connecting said fourth pulley to the smaller of said aligned pulleys, motion-converting driving mechanism for said agitator including a member pivoted to said fourth pulley between the periphery and axis thereof, and means for supporting said aligned pulleys for free movement about a point to one side of their axis whereby they can equalize the tension of said belts.

9. In a laundry machine, rotating and oscillating laundering means, liquid handling means, power operating mechanism for driving said means comprising a vertically arranged motor having a belt pulley on its armature shaft, a belt connected to the pulley of said motor for driving said rotating laundering means and said liquid handling means, a pair of speed reducing, axially aligned, interconnected pulleys rotatably carried by the machine, one of said interconnected pulleys being in engagement with said belt, a second belt engaging the other of said interconnected pulleys, an enlarged pulley rotatably carried by the machine and driven by said second belt, motion converting means including a member pivotally engaging said enlarged pulley at one side of the axis thereof for driving said oscillating laundering means, and means for shifting the axis of said interconnected pulleys, for adjusting the tension of said belts.

10. In a machine of the class described, a base, a plate secured to said base in a readily detachable manner, and an operating mechanism comprising independently mounted parts, some secured to said base and others secured to said plate, such parts of said mechanism being joined to each other in operative relation by slidably interfitting mechanical connections and power transmission belt means, and means for adjusting such mechanical connections for varying the amplitude of the stroke of the machine and thus varying the intensity of the washing action.
11. In a washing machine of the type having a tub for clothes and washing fluid and an agitator oscillatably positioned therein, driving mech-

anism for the agitator comprising a motor having a belt pulley on its shaft, a belt connecting the pulley of said motor to the larger of a pair of joined and axially aligned pulleys rotatably carried by the machine, a fourth pulley of considerably larger size than the largest of the previously mentioned pulleys positioned centrally below the tub, a belt connecting said fourth pulley to the smaller of said aligned pulleys, motion-converting driving mechanism for said agitator including an eccentrically connected member driven by said fourth pulley, and means for shifting the axis of said aligned pulleys for simultaneously adjusting the tension of said belts.

JAMES B. KIRBY. 15
